RECEPTACLE CLOSURE FOR SIFTER CANS,
AND THE LIKE

Alfred I. Cone, New York, N. Y.

Application August 2, 1933, Serial No. 683,275

5 Claims. (Cl. 221—62)

This invention relates to improvements in receptacle closures for sifter cans and the like, and has for an object to provide an improved construction adapted to keep the container normally closed, but so constructed as to be readily operated for the discharge of the contents by manual or digital pressure.

A further object of the invention is to provide a spring-operated self-closing dredge of relatively simple construction, easy of operation, without any projecting operative parts, and having a spring of such form and so related to the operative parts as effectively to force the latter to closing position with appreciable force, whereby accidental opening of the closure by infants will be effectively guarded against.

The dredging device herein disclosed may be applied to containers of varying shape, and made of various kinds or combinations of material. Thus, if desired, for the purpose of economy, for instance, the body of the container may be constructed of fibrous material in combination with a metal operating unit.

Other objects will appear as the nature of the invention is better understood, and the same consists in the novel form, combination and arrangement of parts hereinafter more fully described and shown in the accompanying drawing and claims.

30 The drawing shows a preferred embodiment of the principle of the invention herein disclosed. Obviously, minor changes in detail and form of construction may be made without departing from the spirit and scope of the invention.

35 In the drawing, like reference characters indicate corresponding parts throughout the several views.

Figure 1 is a top plan view of a dredging can, constructed in accordance with the principle 40 of the present invention.

Figure 2 is a broken elevational side view of the device shown in Figure 1.

Figure 3 is a cross-sectional plan view, at the line 3—3 in Figure 2, of the surmounting cap in 45 Figure 2, showing the relation of the operating parts.

Figure 4 is a bottom plan view, showing the relation of the assembled operating parts shown in Figure 3.

50 Figure 5 is a cross-sectional view showing the relation of the operating parts of the container taken upon the line 5—5 in Figure 1 when in the normal closed position.

Figure 6 is a similar vertical cross-section of 55 the container, showing the relationship of the

structure when the operating parts of the container are in relative position for the discharge of the contents.

Referring more in detail to the drawing, a preferred embodiment of the invention is shown in connection with an outer cap 1, suitably mounted upon the container 3, the central upper part of the cap 1 being provided with an opening 4, the side wall of the cap also being provided with a plurality of perforations 5 through which the contents of the can are dispensed when the slots 7 of an inner sleeve 6 are brought into register therewith.

The inner sleeve 6 is closed at the top 11 and provided at the sides with perforations 7, which are so arranged as to size, number and shape that, when the inner sleeve 6 is depressed, an effective number of openings 7 therein will register with a multiplicity of the perforations 5 in the outer cap 1. The bottom of the cap 1 is provided with a plurality of inwardly turned lugs 8 which may be integral with the wall of the cap 1, said lugs serving as supports for the base of a single volute helical spring 9, and serving also to arrest the downward movement of the inner movable sleeve 6 when the latter is operatively depressed, the said spring 9 resting at the upper end against the closed top wall 11 of the inner movable sleeve 6.

In operation, when it is desired to dispense the contents of the receptacle, the same is tilted and the inner movable sleeve 6 is depressed by digital pressure until arrested in its downward movement by the lugs 8. The apertures 7 will then register with a multiplicity of the perforations 5 in the other member, whereupon some of the contents may be dredged or sprinkled through the aligned apertures. The depression of the inner movable sleeve 6 is resiliently resisted by the spring 9 and, when pressure has been removed, the sleeve 6 will be returned to the normal position of closure, as shown in Figure 5.

It will be seen that the contents of the receptacle may thus be easily dispensed whenever desired, by the positive and deliberate application of the required force to the flat top 11 through the opening 4 of the outer cap, but that no discharge can occur accidentally by the casual handling or toying of the container by an infant.

I claim:—

1. A self-closing container top, comprising an inner sleeve open at its lower end and closed at the top, slidably engaged within a cap body of the same general configuration; the said cap body being provided with inwardly turned lugs at its

105

110

lower end and a top wall provided with an opening; the said slidable inner sleeve being restricted in its downward movement by the said lugs at the lower end of the said outer cap body, and restricted in its upward movement by the partly closed top wall of the outer cap body; a helical spring placed within the said inner sleeve and resting at its lower end on the said lugs at the lower end of the outer cap body and pressing at its upper end against the closed top wall of the inner sleeve, it being so disposed as to normally force the closed top of said inner sleeve against the partly closed top of the outer cap body; the side walls of the inner slidable sleeve being provided with apertures so disposed as to permit them to register with perforations in the side wall of the said outer cap body, when the said inner sleeve is in a position of full depression, and completely out of register when all pressure upon the operating spring has been released.

2. A spring-operated closing device for a dredging can, mounted upon a container body, comprising a hollow cylindrical outer member and an inner slidable sleeve member, the said inner sleeve being wholly open at one end and closed by a top wall at the other end and provided with laterally elongated apertures, the said inner slidable sleeve being set within the outer member and restrained in its downward sliding movement by lugs attached to the outer member and in its upward movement by the partly closed top wall of the said outer member, the said outer member being provided with a multiplicity of perforations so disposed and adapted to register with the apertures of the inner slidable sleeve when the latter is fully depressed into operative position, but to be fully closed by the unperforated portions of the side wall of the inner slidable sleeve when the same is allowed to return to its normal position by release of pressure exerted upon its closed top wall through the opening in the top wall of the outer member, through the action of a helical spring longitudinally placed within the hollow of the inner slidable member, the lower end of said spring resting upon the inwardly turned lugs of the said outer member and at its upper end against the closed top wall of the inner slidable member.

3. A self-closing dredging container comprising a container body in combination with a closing device surmounted thereupon, the said closing device consisting of an outer cylindrical member open at its lower end, provided with a partly open top wall consisting of an inwardly turned flange and provided at its open lower end with inwardly turned lugs, and a slidable sleeve member entirely open at the lower end and with a closed top wall at the opposite end slidably set within the hollow of the outer member, its downward movement being restricted by the inwardly turned lugs at the lower end of the outer member and its upper movement by the inwardly turned flange of the said outer member, a single volute helical spring, placed within a slidable sleeve member, and resting at its base upon the said inwardly turned lugs of the outer member and its upper end against the closed top wall of the inner slide-

able member; both the outer member and the inner member being provided with a multiplicity of perforations so disposed and arranged as to come into registry when the inner slidable member is fully depressed through digital pressure upon its closed top wall through the opening in the inwardly turned flange comprising the top wall of the outer member.

4. A self-closing dredging unit for a dusting-powder container, comprising two hollow elongated members of the same general contour, one disposed slidably within the other, both members being of such a form and diameter that the outer side wall of the inner member fits snugly against the inner side wall of the outer member, the said inner member being open at its lower end and closed with a top wall at the other end and being relatively shorter in its longitudinal dimension than the outer member; the outer member being provided at its upper end with an inwardly directed flange adapted to limit the upward movement of the contained inner member and a multiplicity of inwardly turned lugs at its lower open end adapted to limit the downward movement of the said inner member; both of said members being perforated in their side walls and with the perforations so disposed that a portion at least of the two sets of perforations will be brought into registry when the inner member is at the lowest point of its downward movement relatively to the outer member and kept out of registry in all other relative positions; and in combination with both members, an actuating coil spring placed within the unit, resting at its lower end upon the said inwardly turned lugs at the lower end of the outer member and pressing at its upper end against the closed top wall of the inner slidable member, the said spring being of a length and resilient power to force the top of the inner member firmly against the flange at the top of the outer member.

5. A self-closing dredging unit for a discharge container comprising two hollow elongated members of the same general contour, one disposed slidably within the other, the inner member being open at its lower end and closed with a top wall at the other end and being relatively shorter than the outer member, the outer member being provided at its upper and lower ends with means to limit the upward and downward sliding movements of the said inner member; both of the said members having perforations in the side wall so disposed that they can be brought into registry by the movement of the inner slidable member with relation to the outer member; and in combination with both members an actuating spring placed within the said unit and so disposed that it will force the inner member to the limit of its upward movement to the normal position of closure and with the perforations in the side walls of the two members out of register; the outer member being provided with an opening at the top end of sufficient dimension to permit the application of actuating force as by digital pressure upon the exposed closed top wall of the inner slidable member.

ALFRED I. CONE.
